UNITED STATES PATENT OFFICE.

WILLIAM A. JAMESON, OF NIAGARA FALLS, NEW YORK.

DESIGN FOR A HANDLE FOR FORKS, &c.

SPECIFICATION forming part of Design No. 25,408, dated April 21, 1896.

Application filed March 13, 1896. Serial No. 583,132. Term of patent 7 years.

To all whom it may concern.

Be it known that I, WILLIAM A. JAMESON, a citizen of the United States, residing at Niagara Falls, in the county of Niagara and State of New York, have invented and produced a new and original Design for Handles for Forks, Spoons, and Similar Articles, of which the following is a specification, reference being had to the accompanying drawing, showing a part thereof.

The figure shows a side elevation of the fork, this view alone being deemed sufficient to illustrate my design.

The handle embodies my design, the dotted lines showing how the handle may be applied to a spoon. The general outline of the handle is of the well-known "oval thread" or "olive" shape. Along the side edges of the fork is located the scroll-border *a a*, which is raised or embossed, extending downward for about two-thirds the length of the handle, terminating in small ornaments or finales *b b*, which extend farther downward and disappear on either side of the shank, leaving about one-fourth of the length of the handle or shank nearest the bowl entirely plain. At the upper end or apex of the handle is a

representation of a shell *c*, which connects the side borders together. In the broader part of the handle is left a shield-like convex space or panel which may be engraved upon. This convex panel or space becomes narrower as it extends downward and connects with the said plain portion of the shank.

The essential features of this design consist of a handle for a fork, spoon, or similar article having the oval thread or olive outline, the representation of a shell at the apex, a raised scroll-border on each side starting from the shell and extending downward for about two-thirds the length of the handle, terminating in ornaments which disappear on either side of the shank, and an oval convex space between the borders and connecting with an entirely plain portion of the shank near the bowl.

What I claim is—

The design for the handle of a fork, spoon or other similar article, substantially as shown and described.

WILLIAM A. JAMESON.
